United States Patent Office

Des. 196,906
Patented Nov. 19, 1963

196,906

PASSENGER TRAILER

Flake E. Dardenne, 4301 Santa Ana St.,
Huntington Park, Calif.

Filed Mar. 1, 1963, Ser. No. 73,763

Term of patent 14 years

(Cl. D14—3)

Fig. 3.

Fig. 4.

Fig. 5.

FIG. 1 is a perspective view taken from the forward right-hand corner of the vehicle;

FIG. 2 is a perspective view taken from the rear left-hand corner of the vehicle;

FIG. 3 is a fragmentary horizontal section through the vehicle looking downwardly;

FIG. 4 is a fragmentary longitudinal vertical section taken substantially upon the line 4-4 upon FIG. 3;

FIG. 5 is a vertical section taken substantially upon the line 5-5 upon FIG. 4 in the direction indicated.

The dominant features of my design reside in the portions shown in full lines.

I claim:

The ornamental design for a passenger trailer, as shown and described.
